UNITED STATES PATENT OFFICE.

WALTER W. SCOTT, OF SAN FRANCISCO, CALIFORNIA, ASSIGNOR OF ONE-HALF TO
LAYTON J. STOGSDILL, OF SAN FRANCISCO, CALIFORNIA.

DESIGN FOR A RADIATOR CAP.

Application filed March 27, 1929. Serial No. 30,639. Term of patent 3½ years.

To all whom it may concern:

Be it known that I, WALTER W. Scott, a citizen of the United States, residing at San Francisco, in the county of San Francisco, State of California, have invented a new, original, and ornamental Design for Radiator Caps, of which the following is a specification, reference being had to the accompanying drawing, forming part thereof.

Fig. 1 is a side elevation;

Fig. 2 is a front view; and

Fig. 3 is a top plan view of a radiator cap, showing my new design.

I claim:

The ornamental design for a radiator cap, as shown.

WALTER W. SCOTT.
